SPECTROSCOPE

Theodore A. Cutting, Campbell, Calif.

Application November 8, 1934, Serial No. 752,093

11 Claims. (Cl. 88—14)

My invention relates to improvements in spectrometers and the object of my improvement is to provide a spectrometer of the diffraction grating type with a new arrangement of slit and lens and a new form of track and slides. Further objects are to provide a cylindrical lens for dispersing and directing the rays of light and novel means for mounting the lens.

In the drawing:

Figure I is a side view of the spectrometer without spark apparatus,

Fig. II is a front elevation of the same,

Fig. III is a vertical section with spark apparatus in side elevation, and

Fig. IV is a front view of the double gap.

The spectrometer has a diffraction grating 1 held in tube 2 by a lining tube, one part of which 3 is below and the other part 4 above the grating 1. A circular disk 5 closes the bottom of tube 2, and a washer 6 partly closes the upper end. Since the rays of light do not pass perpendicularly through the grating 1, the upper end of tube 2 is cut at an angle of about 45 degrees so that the rays will not be obstructed by the walls.

A window 7 opens just below the level of the grating 1 and is narrowed to a slit by the slide 8 held in track 9, fastened longitudinally to the side of the spectrometer by ends clinched over the ends of the tube. Slide 8 may operate in either the upper or lower end of track 9, or there may be two slides, one above and one below.

In place of a slit between slides 8, a cylindrical lens of glass 10 may be substituted. A beam of light striking the curved glass will enter it, be reflected from the inner surface, and again emerge. At certain critical angles the beam of light will be dispersed into its separate colors as by a drop of water in a rainbow. As the beam passes through the grating 1, it is still further dispersed and so produces the desired spectrum.

It has been found that glass cylinders of small diameter give fine clear lines where the source of light is strong, and that cylinders of greater diameter give brighter lines where the source of light is weak. The cylindrical lens 10 is attached to the end of slide 11, part of which runs in the grooves of 9 and part 12 of which lies parallel to the track on the outside. The end of the slide is trifurcated, having a short middle branch 22 bent at right angles to form a rest for the lens, and having two other branches 23 and 24 encircling the ends of the cylinder of glass and holding it in place. The lens may be critically

adjusted by sliding it up or down before the window.

For spectrum analysis it is highly desirable to have two spectra side by side for comparison. The double or multiple gap shown in Fig. IV in which two different metals are bolted together, as for instance, a strip of copper 14 and a strip of zinc 15, serves this purpose. Strip 16 is copper and 17 zinc. With a spark strong enough to leap both gaps in series, two spectra are produced side by side for comparison.

Some substances yield better spectra in a low voltage arc carrying a relatively large current than in a high voltage arc with a small current, but with an alternating current it is often difficult or impossible to operate an arc between metal electrodes. However, by attaching the substance 18 to be examined to the end of spring 19 vibrated by an electromagnet 20, and allowing a current of two or three amperes to flow interruptedly between the substance 18 and a carbon rod, or other mass of substance 21, an arc may be produced. Two dissimilar tips side by side may be used for comparative spectra. The rapid vibration gives the appearance of a continuous arc, and the frequent actual contact of the electrodes maintains the arc.

In another form, the cylinder 10, instead of being of glass may be of polished metal to reflect a flat beam of light into the window 7, or it may be of colored glass to select some particular ray. In case the source of light is a spark, the cylinder may be discarded and in some cases even the slides dispensed with, for when the beam of light is narrow the grating 1 will disperse it without other assistance.

I claim:

1. A spectrometer having a tubular casing, a diffraction grating within and athwart said casing, a tubular lining both above and below said grating, a track external to said casing and parallel thereto and having ends hooked over the ends of said casing, a window penetrating said lining, casing, and the bottom of said track just beneath said grating, a slide for said track, a lens mounted upon said slide, said lens having the form of a right circular cylinder mounted with its longitudinal axis parallel to the plane of the grating, and a disk closing the bottom end of said casing.

2. A spectrometer having a casing, an opaque closure for one end of said casing, a diffraction grating athwart said casing near the open end, a window in said casing between said opaque closure and said grating and close to the edge of said

50

55

grating, a cylindrical lens having its longitudinal axis parallel to the plane of said grating and mounted upon the casing at the window in order to direct light therethrough, and means for holding said cylindrical lens adjustably in such a position.

3. In combination in a spectroscope, a tubular casing, an opaque closure for one end of said casing, a diffraction grating athwart the open end 10 of said casing, a window at the edge of said diffraction grating through the wall of said casing, and a cylinder lens mounted with its axis parallel to the plane of said grating at said window.

15. 4. A spectroscope having in combination a tubular casing, a lateral opening in said casing, slides adjustably closing said opening, a diffraction grating athwart said tubular casing, a transparent cylindrical lens mounted upon one of said 20 slides and having its longitudinal axis parallel to the plane of said grating, tubular means for holding said grating within said tubular casing, and a disk closing the lower end of said casing.

5. A spectroscope having in combination a 25 diffraction grating, a dark chamber beneath said grating, a small window in said chamber just beneath one edge of said grating, a cylindrical light deflecting body mounted upon said chamber with its longitudinal axis parallel to the plane of the 30 grating and adjustably placed at said window for directing a beam of light upon said grating at a large angle of incidence, and a shield above said grating to prevent direct rays of light from striking the upper surface of said grating.

35. 6. A spectroscope having a diffraction grating, a chamber beneath said grating and attached thereto, a window in said chamber at the edge of said grating, a track upon the exterior wall of said chamber, a slide for said track, and a cylindrical lens mounted upon said slide with its axis 40 parallel to the plane of the grating.

7. A spectroscope having a tubular casing, a

diffraction grating athwart said casing, a track running longitudinally along said casing, a window in the side of said casing beneath said track, a cylindrical lens having its axis parallel to the plane of the grating for directing light through 5 said window, and a slide moving in said track and adapted partly to close said window.

8. A spectroscope having a tubular casing with the bottom cut at right angles and the top obliquely, a closure at the bottom of said casing, 10 a diffraction grating athwart the top, a window in the casing just below said grating, a track mounted longitudinally upon said casing, and slides guided by said track for narrowing the window to a slit parallel to the plane of said 15 grating.

9. A spectroscope having a casing, an opaque closure for one end of said casing, a diffraction grating athwart said casing near the open end, 20 a window in said casing between said opaque closure and said grating and close to the edge of said grating, and slit defining means producing a slit parallel to the plane of said grating, adjustably mounted upon said casing and partly closing said window.

10. A spectroscope having in combination a diffraction grating and a cylindrical lens with its axis parallel to the plane of said grating and mounted at the edge of said grating for directing 25 light thereupon.

11. A spectroscope having a casing, an opaque disk at the bottom of said casing, a tube within said casing resting upon said disk, a diffraction grating athwart said casing resting upon said tube, a track member external to said casing and longitudinal therewith with ends bent over the extremities of said casing, a window penetrating said tube, said casing, and said track, and slides operating in said track and partially closing said 35 window.
